Attorney.

UNITED STATES PATENT OFFICE.

PAUL GANGLER, OF ESSLINGEN, GERMANY.

DEVICE FOR FOLDING PAPER BAGS.

Application filed May 15, 1922. Serial No. 561,038.

To all whom it may concern:

Be it known that I, PAUL GANGLER, engineer, a citizen of the Republic of Wurtemberg, residing at 53 Panoramastrasse, Esslingen, Germany, have invented certain new and useful Improvements in a Device for Folding Paper Bags, of which the following is a specification.

My invention relates to a new or improved device for folding or flattening open bags of paper or similar material, preferably of angular cross-section, and consists essentially in the construction, arrangement and manner of operation of the device as will be described in the following specification with reference to the accompanying drawing, showing one construction of the machine by way of example.

In the drawing:

Fig. 1 is a side-elevation of the device and shows in particular those folding elements which effect the flattening out of the bags, these parts being shown in full lines in their starting position and in broken lines in their final position.

Fig. 2 is a plan view of the machine and shows in particular those folding elements, which force the sides of the bags inwards and crease them, the initial positions of these elements being again shown in full lines and the final positions in broken lines.

Fig. 3 shows in full lines a cross-section through the bag to be folded up prior to the folding, and in broken lines a cross-section of the bag after the folding up, and

Fig. 4 is a side elevation of the folded bag.

In the illustrated construction, two substantially parallel to each other movable folding pairs 1, 2 and 30, 31 are used, of which the pair 1, 2 consists of plates of the width of the bag A, and the pair 30, 31 of folding knives. These pairs of folding elements perform an inwardly and rearwardly directed swinging movement, the folding knives 30, 31 entering between the folding plates 1, 2.

In order to effect this movement, the plates 1 and 2 may be hinged by means of lugs 3, 3 and 4, 4 respectively, upon levers 12, 13 and 17, 18 which are keyed upon shafts 50, 51 and 52, 53 rotatable in a suitable and

known manner in stationary bearings not shown. The shafts 50, 51 and 52, 53 are coupled together by connecting links 16 and 21 joining their fixed arms 14, 15 and 19, 20. 55 The oscillating movement of the shafts 50, 51 and 52, 53 may be effected by any suitable common drive, which is therefore not shown in the drawing.

The parallel inward and rearward movement of the folding knives 30 and 31 may be effected in a similar manner to the plates 1 and 2, for instance by the shafts 54, 55 and 56, 57 rotatable in stationary bearings and fitted with the bell-cranks 32, 34; 33, 35; 37, 39; and 45, 40, which are connected by the links 36 and 58. The shafts 54 to 57 may be rotated by any suitable common drive, which is therefore not shown in the drawing. 60

At the front or inlet end of the plates 1 and 2, there are arranged angular plates 22 or 23, fulcrumed by means of hinges 59 and 65 upon pins 25 and 26, disposed at the front ends of the plates 1 and 2. These plates 22 and 23 are adapted to be swung 70 inwards in any suitable known manner, which is therefore not shown, so that they engage corresponding recesses 66 and 67 at the inside of the plates 1 and 2. The plates 1 and 2 are at their opposite or rear ends 75 furnished with pressing plates 61 and 63.

The real enclosure of the folding bag is in the upper half formed by a fixed plate 24 serving as abutment for the bottom of the bag, and in the lower half by a drum 29, 80 85 which is intermittently rotated in the direction of the arrow by the shaft 28 to perform one complete revolution. Means to effect this are well known and therefore not illustrated. The drum 29 consists of single ring- 90 or disc-like portions 29, and the pressing plate 61 of the folding plate 2 consists of fingers or prongs which conform in shape with the spaces between the rings or discs 29, and are therefore capable of passing 95 through these spaces when the folding plate 2 swings towards the drum 29. The pressing plate 63 of the upper folding plate 1 is solid.

As clearly shown in Fig. 1, the drum 29 is provided with a recess 60 and the leading 100 edge 64 of this recess is, with the parts in the positions shown in Fig. 1, in line with

the inside of the abutment 24. A contact or counter drum 27 rotated by the shaft 71 cooperates with the drum 29.

The device operates in the following manner:

The bag A to be folded is pushed or otherwise inserted between the folding pairs 1, 2 and 30, 31, until the bottom of the bag rests against the abutments 24, 64, the holders 22 and 23 being then turned inside and gripping the open or front edges of the bag in conjunction with the recesses 66 and 67. The plates 1 and 2 and the folding knives 30 and 31 are then swung inwards and rearwards, as indicated in Figs. 1 and 2, whereby the folding knives 30 and 31 enter between the folding plates 1 and 2, until the plates 1 and 2 and folding knives 30 and 31 take up the positions shown in broken lines in Figs. 1 and 2. In this position of the folding elements, the sides of the bag have been creased and the bag flattened as shown in broken lines in Fig. 3, by the cooperation of the plates 1 and 2 and folding knives 30 and 31, while the bottom of the folded bag is pressed against the abutment 64 and 24 by the pressing plates 61 and 63.

Now the drum 29 performs a complete revolution, during which the following or rear edge of the recess 60 in the drum engages the lower half of the flattened out bottom of the bag A and carries the bag along, so that the front edge of the bag bottom passes between the drum 29 and the contacting drum 27 and the folded or collapsed bag is withdrawn from the device after the holders 22 and 23 have released the front edges of the bag. During this withdrawal of the bag A, a useful further compression or flattening of the bag, especially of its bottom part, takes place between the drums 27 and 29. The form of the flattened bag coming from the device, is shown by the side elevation illustrated in Fig. 4.

The device or apparatus described and illustrated serves, as already mentioned, to clearly explain the invention. It is therefore obvious that the device shown may be varied and its details modified within the ambit of the claims without departing from the spirit of the invention. It will thus also be understood that the invention is not limited to the construction illustrated.

I claim:

1. In a device for folding angular paper bags, the combination of a top and bottom plate, means for moving said plates substantially parallel towards each other and rearwards, a pair of knives, and means for moving said knives substantially parallel towards each other and rearwards at right angles to said plates.

2. In a device for folding angular paper bags, the combination of a top and bottom

plate, a pair of bell cranks hinged to each of said plates and adapted to move them towards each other and rearwards, a pair of knives and a pair of bell cranks hinged to each of said knives and adapted to move said knives towards each other and rearwards at right angles to said plates.

3. In a device for folding angular paper bags, the combination of a top and bottom plate, a pair of lugs upon the outer face of each of said plates, a pair of bell cranks hinged to said lugs with one arm, a connecting link joining the two other arms of said bell cranks, shafts upon which said bell cranks are keyed, bearings for said shafts, means for rocking said shafts in opposite direction, a pair of knives disposed at the side of said plates, a pair of lugs upon the outside of said knives, a pair of bell cranks hinged to said lugs with one arm, a connecting link joining the two other arms of said bell cranks, shafts upon which said bell cranks are keyed, bearings for said shafts, and means for rocking said shafts in opposite directions so that said knives move towards each other at right angles to and between said plates.

4. In a device for folding angular paper bags, the combination of a top and bottom plate, an angular gripper fulcrumed at the front edge of each of said plates and adapted to engage a recess at its inner face, a pair of lugs upon the outer face of each of said plates, a pair of lugs upon the outside of said knives, a pair of bell cranks hinged to said lugs with one arm, a connecting link joining the two other arms of said bell cranks, shafts upon which said bell cranks are keyed, bearings for said shafts, and means for rocking said shafts in opposite directions so that said knives move towards each other at right angles to and between said plates.

5. In a device for folding angular paper bags, the combination of a top and bottom plate, an angular gripper fulcrumed at the front edge of each of said plates and adapted to engage a recess at its inner face, outwardly extending pressing plates at the rear edge of each of said plates, a pair of lugs upon the outer face of each of said plates, a pair of bell cranks hinged to said lugs with one arm, a connecting link joining the two other arms of said bell cranks, shafts upon which said bell cranks are keyed, bearings for said shafts, means for rocking said shafts in opposite directions, a pair of knives disposed at the side of said plates, a pair of lugs upon the outside of said knives, a pair of bell cranks hinged to said lugs with one arm, a connecting link joining the two other arms of said bell cranks, shafts upon which said bell cranks are keyed, bearings for said shafts, and means for rocking said shafts in opposite directions so that said knives move

towards each other at right angles to and between said plates, and a fixed abutment for the upper and a movable abutment for the lower of said pressing plates upon said top and bottom plates, said lower abutment consisting of a plurality of recessed rotary rings between which the recessed rear edge of the bottom plate is adapted to enter and

a contacting roller cooperating with said rings to deliver the folded bags. ¹⁰

In testimony whereof I affix my signature in presence of two witnesses.
